Primary Examiner — Darlington Ly(74) *Attorney, Agent, or Firm* — Snell & Wilmer LLP(57) **CLAIM**

The ornamental design for a motorcycle as shown and described.

DESCRIPTION

FIG. 1 is a front elevation view of a motorcycle embodying my new design;

FIG. 2 is a rear elevation view thereof;

FIG. 3 is a right side elevation view thereof;

FIG. 4 is a left side view thereof;

FIG. 5 is a top plan view thereof;

FIG. 6 is a bottom plan view thereof;

FIG. 7 is a top-front-right side perspective view thereof; and, FIG. 8 is a top-rear-left side perspective view thereof.

The portions of the motorcycle shown in a ghosted effect or with low contrast/saturation forms no part of the claimed design.

1 Claim, 8 Drawing Sheets(56)
